his ATTORNEYS.

Patented Sept. 21, 1926.

UNITED STATES PATENT OFFICE.

MAX EPSTEIN, OF ROCHESTER, NEW YORK, ASSIGNOR TO HICKOK MANUFACTURING COMPANY, INC., OF ROCHESTER, NEW YORK, A CORPORATION OF NEW YORK.

BELT.

Application filed June 11, 1924. Serial No. 719,263.

The present invention relates to belts and more particularly to means for connecting a belt buckle. An object of this invention is to provide a construction in which the inturned end of a belt carries a device for detachably interlocking with a device on the rear face of the main portion of the belt, the latter device acting as a securing means for the loops through which the free end of the belt is passed. Another object of the invention is to provide a construction in which the inturned end and the rear face of the belt are provided with detachable connecting devices, one of which interlocks with the other by a relative movement of the devices in the direction of the length of the belt, the direction of the interlocking movement being such that the tension on the belt tends to hold the two parts interlocked.

To these and other ends, the invention consists of certain parts and combinations of parts, all of which will be hereinafter described; the novel features being pointed out in the appended claims.

In the drawings:—

Fig. 1 is a face view of one end of a belt showing a buckle connected thereto;

Fig. 2 is a view of the rear face of the belt with the inwardly turned end swung outwardly;

Fig. 3 is an enlarged fragmentary section through the belt showing the device on the inwardly turned end interlocked with the device on the rear face of the rear portion of the belt;

Fig. 4 is a section on the line 4—4, Fig. 3;

Fig. 5 is a view similar to Fig. 2, of another embodiment of the invention; and

Fig. 6 is a fragmentary section of an embodiment of the invention shown in Fig. 5.

Referring more particularly to the embodiment of the invention illustrated in Figs. 1 to 4, 1 indicates a fragment of the main portion of the belt and 2 indicates the end turned inwardly on the inner face of the belt to provide a loop for connecting with the anchoring member 3 of a belt buckle 4. Secured to the rear face of the main portion of the belt is a connecting device 5, in this instance, in the form of a plate having prongs 6 arranged in pairs at opposite ends and passing through the ends of loops 7 which extend about the belt to receive the free ends of the belt beneath them after the latter has been passed through the buckle 4. In addition to passing through the ends of the loop 7, the prongs 6 pass through the main portion of the belt and are bent over on the front face of the main portion 1 and beneath the loops. On the inner face of the inwardly turned portion 2 is another connecting device 8 in the form of a plate secured in any suitable manner as by rivets 9. The two connecting devices have interlocking means thereon which are caused to interlock by a relative movement of the two members in the direction of the length of the main portion 1 of the belt. These interlocking devices, in this instance, comprise tongues 10 cut from the plate 8 and bent from the plate so as to project laterally. These tongues are adapted to enter offset pockets 11 formed on one side of the plate 5, the latter being provided with slots 12 permitting the entrance of the prongs 10 into the pockets.

In the embodiment of the invention illustrated in Figs. 5 and 6, the plate 5^a, in addition to having the prongs 6^a secured by loops 7, has transversely extending pressed up portions 6^b which receive the ends of the loops 7 and take some of the strain off the securing prongs 6^a. The plate 5^a also has tongues 12^a with shoulders 12^b formed thereon. The plate 8 on the inturned end of the belt secured by rivets 9^a is formed with pockets 10^a and slits 10^b leading to such pockets. Inside of the pockets shoulders 10^c are provided for engagement with the shoulders 12^b on the tongues 12^a, the tongues 12 yielding in order that the shoulders 12^b thereof may engage beyond the shoulder 10^c.

In all embodiments of the invention, the main portion of the belt and the inwardly turned portions of the belt are provided on their opposed face with interlocking devices which are brought into and out of interlocking connection by a relative movement of the devices on the two parts in a plane parallel with the main portion of the belt. In the two illustrated embodiments of the invention, a device on the rear face of the main portion of the belt for interlocking with devices on the inwardly turned portion of the belt, is utilized for securing the loops to the main portion of the belt. In all forms of the invention the pull of the belt buckle on the connection is such that it tends to hold the interlocking devices together. By this construction the front of the belt is free from any fastening devices and the strain on the

belt is not such that the interlocking devices will be disconnected.

What I claim as my invention and desire to secure by Letters Patent is:—

1. A belt comprising a main front portion, an inwardly turned portion at one end of the front portion, loops on the main front portion, and interlocking devices on the opposed faces of the main front portion and the inwardly turned portion, the interlocking devices on the main front portion having prongs for securing the loops to the main front portion.

2. A belt comprising a main front portion, an inwardly turned portion at one end of the main front portion, loops on the main front portion having their ends extending over the rear face of the main front portion, a plate having prongs passing through the ends of the loops on the rear face of the main front portion and through the main front portion beneath the portions of the loops on the front face of said main front portion, and means carried by the inwardly turned portion having connection with the plate to hold the inwardly turned portion to the main portion.

3. A belt comprising a main portion and an inwardly turned portion on the inner side of the main portion, interlocking devices on the opposed faces of the main portion and the inwardly turned portion, the interlocking devices on one of said portions embodying two tongues extending in such a direction that the pull on the belt tends to hold the tongues in interlocking relation with the devices on the other part.

4. A belt comprising a main portion and an inwardly turned portion at one end and on the inner side of the main portion, interlocking devices on the opposed faces of the

two portions, the interlocking devices on one of said portions being in the form of a plurality of tongues extending laterally in one and the same direction and the interlocking devices on the other side of said portions embodying pocketed portions having openings at one side in which the tongues on the other portion of the belt are adapted to be received.

5. A belt comprising a main portion and an inwardly turned portion at one end and on the inner side of the main portion, two plates secured to the faces of the opposed portions of the belt, one of said plates having a plurality of tongues extending in one and the same direction and the other of said plates having pocketed portions formed with openings in one side in which the tongue is adapted to be received.

6. A belt comprising a main portion, an inwardly turned portion at one end thereof and on the inner side of said main portion, loops on the main portion having their ends extending on the inner side of such main portion, a plate having prongs passed through the ends of the loops and through the main portion of the belt beneath the front portions of the loops, and means on the inner face of the inwardly turned portion for interlocking with said plate.

7. A belt comprising a main portion, an inwardly turned portion at one end and on the inner side of the main portion, loops on the main portion having their ends extending on the rear side of said main portion, a plate having transverse depressions on its inner face receiving the ends of the loops, and means on the inwardly turned portion for interlocking with said plate.

MAX EPSTEIN.
